UNITED STATES PATENT OFFICE

JOHN H. WHITWELL, OF PHILADELPHIA, PENNSYLVANIA

DESIGN FOR WALL PAPER

Application filed June 21, 1929. Serial No. 31,794. Term of patent 3½ years.

To all whom it may concern:

Be it known that I, JOHN H. WHITWELL, a citizen of the United States, residing at Philadelphia, in the county of Philadelphia and State of Pennsylvania, have invented a new, original, and ornamental Design for Wall Paper, of which the following is a specification, reference being had to the accompanying drawing, forming a part thereof.

The figure on the drawing is a plan view of a piece of wall paper bearing my new design which is intended to be carried forward or repeated ad libitum, as shown. The

shading is on the drawing only to indicate relatively contrasting colors and not to indicate specific colors.

A single unit of my design is substantially comprised within the area defined by the indicating lines and arrows shown on the drawings, which lines and arrows however form no part of my design.

I claim:

The ornamental design for wall paper substantially as shown.

JOHN H. WHITWELL.
